Attorney

UNITED STATES PATENT OFFICE.

WALTER PACK, OF TAKOMA PARK, MARYLAND, ASSIGNOR TO CHARLES A. ROGERS, OF HARTFORD, CONNECTICUT.

SENSITIZED-ELEMENT PACKAGE FOR PHOTOGRAPHIC APPARATUS.

1,424,736.

Specification of Letters Patent.

Patented Aug. 1, 1922.

Original application filed January 29, 1921, Serial No. 441,019. Divided and this application filed July 11, 1921. Serial No. 483,764.

To all whom it may concern:

Be it known that I, WALTER PACK, a citizen of the United States, residing at Takoma Park, in the county of Montgomery and State of Maryland, have invented certain new and useful Improvements in Sensitized-Element Packages for Photographic Apparatus; and I do hereby declare the following to be a full, clear, and exact description of the invention, such as will enable others skilled in the art to which it appertains to make and use the same.

This invention relates to sensitized element packages for photographic apparatus and has for its object to provide a package of this character which will be simple and comparatively inexpensive to manufacture, and which may be readily and efficiently employed with plate or film holders such, for example, as the type disclosed in my copending application filed January 29, 1921, Serial Number 441,019, entitled "Magazine film and plate holders for cameras", of which this application is a division.

With these and other objects in view, the invention consists in the novel details of construction and combinations of parts more fully hereinafter disclosed and particularly pointed out in the claims.

Referring to the accompanying drawings forming a part of this specification, in which like numerals designate like parts in all the views:

Figure 1 is a diagrammatic horizontal sectional view of a plate and film holder of the type disclosed in my said copending application, showing the present film package in place therein, before the envelope is removed;

Figure 2 is a view similar to Figure 1, but looking in the opposite direction, illustrating the envelope partially removed;

Figure 3 is a diagrammatic plan view of a blank from which the light tight envelope is formed;

Figure 4 is a diagrammatic elevational view of a film package, showing the envelope partially removed; and

Figure 5 is a fragmentary elevational view of a slight modification employed in adapting a glass plate for use with the form of envelope shown in Figures 3 and 4.

Referring more especially to Figures 3 and 4, 1 designates a sensitized element, such

as a photographic film, one end of which is provided with the angularly disposed edges 2 and 3, and with a small perforation 4. The said element is normally enclosed before exposure in a light tight envelope 5, of the well known light proof paper, or other suitable material, which envelope is preferably folded from a blank 6, such as that shown in Figure 3.

In preparing this envelope, the member 7 of the said blank is first folded over along the dotted line 8, whereupon the member 9 is folded over in the same direction along the dotted line 10, and its edge 11 secured in any suitable manner, as by adhesives, to the member 7. In like manner the member 12 is folded over along the dotted line 13 and its edges 14 and 15 secured by adhesives to the surfaces of the members 7 and 9 respectively. This produces a package having a pointed tab 16, as seen in Figure 4, comprising a lower member 17, and an upper member 18, composed of the pointed ends 19 and 20 of the members 9 and 12. The inner surfaces of the members 17 and 18 may be secured together by adhesive after the sensitized element has been inserted in the envelope by the manufacturer, and the tab 16 is folded over along the line 21, thus providing a completely sealed light tight enclosure for the element 1.

25 indicates any form of film or plate holder suitable for use with the usual camera or other photographic apparatus, here illustrated as of the type disclosed in my said copending application Ser. No. 441,019. 90 The said holder may comprise a rectangular frame 26, provided with a pair of dark slides 27 and 28, forming a magazine 29 for the reception and retention of exposed films or plates, as is disclosed in the said copending application. The said frame 26 may carry a detachable frame 30, which is provided with a hinged gate or door member 31, adapted to swing outwardly from the frame 30, to permit of the introduction of the sensitized element package and the said frame 31 is further provided with a pin or projection 32 adapted to enter the perforation 4 of the film 1, all as will appear more fully below.

The mode of using the present invention will be clear from the foregoing, but may be briefly summarized as follows:

Supposing the parts of the holder 25 to be

in the positions illustrated in Figures 1 and 2, without a sensitized element therein, the hinged member 31 is first swung away from the frame 30, and a package comprising an envelope 5 with its enclosed film 1, is placed between the said member and frame, its tab 16 being unfolded to a position similar to that illustrated in Figure 4. The hinged member 31 is then swung back toward the frame 30, to its initial position, and a suitable catch, not shown, serves to hold it there. The pin or projection 32, carried by the said member 31, penetrates the dark paper envelope 5, and passes through the perforation 4 in the film 1.

The device is then ready for insertion into the camera in the usual manner, and after it has been so placed therein, the sensitized element 1, which has up to this time been completely protected from light by its said envelope 5, is finally prepared for the exposure.

This is accomplished by grasping the tab 16 of the envelope 5, which will project out to one side of the camera somewhat after the manner of the well known film packs, and pulling upon the same. The pin 32 carried by the member 31, having passed through the perforation 4 in the film 1, will hold the latter against movement, while it will tear through the relatively thin paper envelope 5, as indicated in Figure 4. The end 22 of the envelope 5 will be forced against the point 23, formed at the intersection of the angularly disposed edges 2 and 3 of the film 1, and the said edges will cut the said end 22, somewhat after the manner of a knife, thus permitting the envelope to be withdrawn from the film, leaving the latter in a position in the holder 25 to be subjected to the action of light from the camera lens.

The envelope 5, after it has been withdrawn, may be discarded, since it has served its purpose and is no longer required.

If it be desired to use glass plates instead of the flat celluloid films, the said plates may be cut and perforated in the same manner as the films. However, a less expensive method, and one which has proven in actual practice to be just as efficient, is to employ the usual rectangular plates, such as 35, illustrated in Figure 5, and to attach a small sheet metal member 36 to one edge thereof, by means of suitable stickers or holding members 37. The said members 36 may be provided with a perforation 38, and with the angularly disposed edges 39 and 40 meeting at a point 41, similar to the corresponding perforation and edges above described in connection with the film 1.

The plates when so constructed, may be used in substantially the same manner as the films.

It is obvious that those skilled in the art 65 may vary the details of construction as well as the arrangement of parts without departing from the spirit of the invention, and therefore I do not wish to be limited to the above disclosure except as may be required 70 by the claims.

What I claim is:

1. A photographic sensitized element package comprising a sensitized element provided with a severing portion, and surrounded by a completely sealed enclosing member which is adapted to be opened by cutting contact with said severing portion, substantially as described. 75

2. A photographic sensitized element package comprising a sensitized element provided with a cutting edge, and enclosed in a completely sealed light excluding envelope adapted to be opened by cutting contact with said cutting edge, substantially as described. 80

3. A photographic sensitized element package comprising a sensitized element provided with an angularly disposed cutting edge, and enclosed in a completely sealed light excluding envelope adapted to be opened by cutting contact with said cutting edge, substantially as described. 90

4. A photographic sensitized element package comprising a sensitized element provided with a pair of angularly disposed severing edges intersecting to form a penetrating point, said element being enclosed in a completely sealed light-excluding member adapted to be opened to permit the removal of said cutting element, by contact with said point and severing edges, substantially as described. 95

5. A photographic sensitized element package comprising a sensitized element provided with a separable member having a pair of angularly disposed severing edges intersecting to form a penetrating point, said element and member being enclosed in a completely sealed light-excluding member adapted to be opened to permit the removal of said element, by cutting contact with said point and severing edges, substantially as described. 100

6. A photographic sensitized element package comprising a substantially rigid sensitized element provided with a separable member having a pair of angularly disposed severing edges intersecting to form a penetrating point, said element and member being enclosed in a completely sealed light-excluding member adapted to be opened to permit the removal of said element, by cutting contact with said point and severing edges, substantially as described. 115

In testimony whereof I affix my signature.

WALTER PACK.
